SPRING BOLT

Joseph H. Oswald, South Euclid, and Theodore E. Weil, Willoughby, Ohio

Application July 1, 1947, Serial No. 758,296

3 Claims. (Cl. 292—175)

1

The invention relates to locking or fastening devices of the spring bolt type.

It is an object of the invention to produce a spring bolt which can easily be mounted in a wood window sash or other panel structure by simply forcing it into a hole drilled to receive it and which is not likely to loosen or be dislodged in use.

Another object of the invention is to provide a spring bolt having parts that can be manufactured at low cost and easily assembled to produce a device that is both rugged and durable and unlikely to get out of order.

With these ends in view the invention consists in certain forms, combinations and arrangements of parts which will hereinafter be explained and claimed, the explanation being presented in conjunction with the accompanying drawing showing a preferred form of the various constructions in which the invention can be embodied.

In the drawing,

Fig. 1 is a fragmentary inside elevation of a window sash and frame with the improved spring bolt mounted in the sash.

Fig. 2 is a view on a larger scale of the unmounted spring bolt, the view being partly in longitudinal axial section and partly in side elevation.

Fig. 3 is a section on the line 3—3 of Fig. 2.

In the construction shown in the drawing A (Fig. 1) designates a portion of a window frame, B part of the stile of an associated window or storm sash and C designates generally the improved spring bolt mounted in the sash. The construction of the spring bolt is shown in detail in Figs. 2 and 3 where the numeral 1 designates as an entirety a tubular casing which is formed at one end with an inturned flange 1a. Adjacent one of its ends the casing 1 has an annular portion of its exterior surface knurled and preferably this knurling is disposed adjacent the end of the casing remote from the flange 1a, as is shown at 1b in the drawing. This knurling of the casing is carried out in a manner to raise sharp edges so that the overall diameter of the knurled zone is slightly (preferably about 0.020") greater than the diameter of the unknurled part of the casing.

Slidably mounted in the casing 1 is a round bolt designated as an entirety by the numeral 2 and having a portion 2a of larger diameter than a second portion 2b with a resultant shoulder 2c at the junctions of these two portions. Adjacent the larger portion 2a the bolt is formed with a

conical taper 2d which terminates in a rounded end 2e.

A coil spring 3, preferably of stainless steel, surrounds portion 2b of the bolt with one end 5 of the spring engaging the shoulder 2c of the bolt and its other end engaging the flange 1a of the casing.

The bolt is fitted with a handle member 4 which in the construction shown is of straight rod-like form and has at one end an axial hole 4a drilled of a size to fit the end of the smaller sections of the bolt which projects beyond the flange 1a of the casing. To fasten the handle rigidly to the bolt the latter is notched and the handle is locally deformed to interlock with the notch. Preferably two such interlocking engagements are provided by oppositely arranged notches 2f, 2g in the bolt and corresponding indented portions 4b, 4c of the handle.

20 A spring bolt structure such as that shown and described is susceptible of manufacture at remarkably low cost. All of the parts except the spring 3 are preferably formed of brass and with the exception of two operations the parts can be rapidly produced on automatic screw machines. The casing 1 is, of course, formed from tubing and can have its knurled zone 1b rapidly formed. The flange 1a of the casing can be formed by a combined cutoff and spinning operation. The bolt 2 and handle 4 are formed from plain round rod stock and their several forming operations are obviously well suited to screw machine work except for the notching of the bolt and the deforming of the handle to effect its attachment to the bolt. These latter two operations, however, are readily carried out. The notching of the bolt 2 is effected by holding the cylindrical bolt in a die having a cavity of corresponding shape so that when the metal of the bolt is deformed to produce the opposite notches 2f the displacement of the metal is accommodated by endwise movement in the die so that the overall diameter of the bolt is not altered. The deforming of the handle part to effect its interlock with the bolt is obviously a simple and easily performed operation.

25 The use of a stainless steel spring has a marked advantage over a bronze spring by reason of its longer life without loss of form; and the cost of the stainless steel spring is as low or lower than that of a good bronze spring.

In the use of the spring bolt a hole is drilled in the window sash of a diameter equal to the outer diameter of the unknurled part of the spring bolt casing. With the form of spring bolt which

has been shown and described, having the knurled zone $1b$ remote from the handle of the device, the spring bolt is introduced into the hole in the sash from the outer edge of the sash stile. Thus the knurled portion $1b$ does not engage the wall of the hole in the wood until the insertion is nearly completed. As the knurled surfaces engage the wood the resistance to the inward movement of the bolt casing is, of course, substantially increased but the insertion is nevertheless readily effected. Once inserted the bolt casing is held with great firmness so that it cannot be dislodged in the ordinary use and operation of the device. It has been observed that the effect of the knurled surface of the bolt casing, when the casing is inserted in the sash, is that the sharp metal edges thrown up by the knurling operation shave a thin layer of the wood from the hole surface and compact it between the casing and the solid wood. Thus in effect a tight pressed fit is attained with respect to the relatively narrow knurled band while a less tight, but firm, fit is secured between the remainder of the casing member and the wood of the sash.

It will be appreciated that the manner of attaching the handle to the spring bolt effects a strong and rigid connection which cannot be loosened for either endwise or rotary relative movement of the parts to cause trouble in the use of the device. A series of handle members can be formed of different lengths (by varying the dimension x indicated in Fig. 2 of the drawing) and simply by the use of these handles of different lengths spring bolts suited to sash stiles of different widths can be produced without varying the dimensions of the other parts of the device.

It will be understood that the specific form of

construction which has been shown in the drawings and described, is presented for the purposes of explanation and that the structures shown can be modified in various respects without departing from the invention as defined in the appended claims.

What is claimed is:

1. In a spring bolt, the combination of a tubular casing formed at one end with an inturned flange and having adjacent one end an annular zone of its outer surface knurled to an over-all diameter somewhat larger than the diameter of its unknurled surface; a round bolt in the casing formed with two portions of different diameters separated by an annular shoulder facing the inturned flange of the casing, the bolt having its larger portion slidably fitting the casing and its smaller portion projecting from the flanged end of the casing and laterally notched to receive a handle; a coil spring surrounding the smaller portion of the bolt with its ends engaging the shoulder of the bolt and the flange of the casing, respectively; and a handle for the bolt formed with a hole to receive the notched portion of the bolt and deformed to have interlocking engagement with the notch.

2. A spring bolt as claimed in claim 1 in which the knurled surface of the casing is adjacent the end of the casing remote from its inturned flange.

3. A spring bolt as claimed in claim 1 in which the knurled surface of the casing is adjacent the end of the casing remote from its inturned flange and the handle is of straight rod-like form with an axial hole to receive the bolt.
